Charlestown Att # UNITED STATES PATENT OFFICE.

WILLIAM DEANE HAM, OF CHICAGO, ILLINOIS.

CONCRETE-ROAD-BUILDING MACHINE.

1,345,925.

Specification of Letters Patent.

Patented July 6, 1920.

Application filed September 28, 1916. Serial No. 122,611.

To all whom it may concern:

Be it known that I, WILLIAM DEANE HAM, a citizen of the United States, and a resident of the city of Chicago, in the county 5 of Cook and State of Illinois, have invented certain new and useful Improvements in Concrete-Road-Building Machines; and I do hereby declare that the following is a full, clear, and exact description of the same, 10 reference being had to the accompanying drawings, and to the numerals of reference marked thereon, which form a part of this specification.

This invention relates to an improved type 15 of concrete mixing and laying or distributing machine, wherein power driven mechanisms serve to operate the mixer, which is mounted upon a truck and may be moved under its own power as the work progresses, 20 at the same time rolling the surface over which the concrete is to be laid. This machine is particularly adapted for use upon roadways, side walks and other similar concrete construction projects.

25 It is an object of this invention to construct a machine embodying a frame having a mixer mounted thereon, as well as an engine for driving the same, together with means for moving the machine along as the work progresses, feeding a reinforcement 30 fabric therealong over which the concrete is discharged from the mixer and embodying a compact arrangement of the parts for the greatest efficiency and ease of operation.

35 It is also an object of this invention to construct a concrete mixing and distributing machine mounted upon a truck frame for movement from place to place, and provided with power driven mechanisms which are 40 adapted, through suitable means, to operate the different elements of the machine, and with measuring means associated with the machine to properly proportion the ingredients of the charge to be admitted into the 45 mixer, thus simplifying the operation of the machine, and reducing the time and number of men in the crew generally required.

It is furthermore an object of this invention to construct a concrete machine, embodying a power plant and mixer together 50 with a water reservoir and receiving hopper so that the proper quantity of water and mixture may be admitted from the receiving hopper into the mixer immediately after 55 discharge of the contents thereof, and with

an unloading platform leading to the hopper affording an inclosing hood for the power plant.

It is finally an object of this invention to provide an improved form of concrete mixing and laying machine, wherein the reinforcement fabric is unreeled from the machine as the same moves along, receiving the concrete discharged thereover, and with clutch controlled power means for operating 60 the different mechanisms of the machine in the most efficient manner possible.

The invention (in a preferred form) is illustrated in the drawings and hereinafter more fully described. 70

On the drawings:

Figure 1 is a side elevation of a machine embodying the principles of my invention, showing the same in use.

Fig. 2 is an enlarged side elevation of the 75 machine with the operation of one element shown in dotted lines.

Fig. 3 is a top plan view of the machine as shown in Fig. 1.

Fig. 4 is a front end view of the machine 80 with parts shown in section.

Fig. 5 is a top plan view of the machine, with the mixer drum omitted and with parts broken away.

Fig. 6 is a detail section taken on line 85 6-6, of Fig. 5, with parts omitted.

Fig. 7 is a sectional detail taken on line 7-7, of Fig. 6.

Fig. 8 is a fragmentary detail section taken on line 8-8, of Fig. 4. 90

Fig. 9 is a detail section taken on line 9-9, of Fig. 2.

Fig. 10 is a top sectional detail illustrating the pivot connection for one of the front 95 rollers of the machine.

Fig. 11 is a side sectional detail illustrating the means of replacement of a roller by a stationary supporting foot.

As shown on the drawings:

The frame of the machine consists of 100 channel irons forming side sills 1, a rear end sill 2, and a front end sill 3. Said frame is reinforced centrally by an intermediate transverse beam 4, extending between the sills 1, and parallel to the end sills 2 and 3. 105 Mounted at the rear end of the frame are four uprights 5, and secured at the upper ends of each thereof are longitudinal and transverse beams 6, with the structure thus formed braced at the corners by angle mem- 110

bers 7. Bearing brackets 8, are secured to the side sills 1, at the rear end of the machine, and mounted transversely of the machine therein, is an axle 9, upon which a 5 number of rollers 10 and 11, respectively, are journaled as clearly shown in Fig. 5, upon which the rear end of the machine is supported. At the front end of the machine as clearly shown in Figs. 2 and 10, corner 10 brackets 12, are secured on the inner surfaces of the junction of the side sills 1, and front end sill 3, said corner brackets being provided with a vertical pivot bearing 13, through which extends a pivot shaft 14, on 15 the lower end of which is formed a yoke 15, in which is journaled a roller 16. Said rollers 16, have a caster effect so that the machine may be guided as it is moved along.

Referring to Fig. 5, there are two sub-sill 20 frame members 17, extending between the sill 3, and the intermediate beam 4, to afford a support for a gasolene engine 18. A pair of bearing brackets 19 and 20, are mounted upon said intermediate beam 4, 25 and another pair of bearing brackets 21 and 22, are mounted upon the end sill 2, and journaled in and between the bearing brackets 19 and 21, is a shaft 23, and similarly journaled in the bearing brackets 20 and 22, 30 is another shaft 24. Secured upon said respective shafts 23 and 24, are roller wheels 25, and supported thereon is a cylindrical concrete mixer 26, of a conventional type provided with peripheral tracks or grooves 35 27, into which said roller wheels 25, engage, to rotatably support the mixer in position. Journaled upon the shaft 24, is a gear 28, and feathered upon said shaft adjacent thereto, is a clutch member 29, adapted to 40 engage with the hub of said gear to lock the same upon the shaft 24, for rotation therewith. Secured upon the periphery of the mixing drum or cylinder 26, as clearly shown in Fig. 2, is a ring gear 30, in mesh 45 with said driving gear 28, so that by engagement of the clutch member 29, said mixer may be caused to rotate, thereby mixing the ingredients of the charge introduced into the mixing drum. A hopper 31, is 50 mounted upon the front end of the drum 26, adapted to discharge thereinto through a central opening, and slidably mounted within said hopper 31, as shown in Fig. 4, is a vertically movable gate valve 32, movable between guides 33, and adapted to close 55 over the opening in the mixing drum 26, leading from the hopper 31. A link 34, is connected upon said gate valve 32, and is also connected to a lever 35, pivoted on the 60 frame for actuation of said gate valve into open and closed position.

At the other or rear end of the mixing cylinder 26, a discharge chute or spout 36, is pivoted, as shown in Fig. 2, and is provided with a handle 37, whereby the same

may be tilted upwardly to prevent discharge of the contents of the mixer if so desired. As shown, a relatively long chute 38, is connected to the frame of the machine, beneath the spout 36, and tracks over 70 the ground discharging the concrete which is denoted by the reference numeral 39, after which the concrete is spread over the reinforcement fabric 40, which is unwound from a reel of the fabric, the axle of which 75 is connected in slotted arms 41, secured on the rear end of the machine. A tamping plate 42, having a curved edge is towed behind the machine by cables 43, connected at each side thereof, and the concrete 39, is 80 smoothed and tamped by a man standing upon the plate and delivering the tamping blows to the plate itself.

Supported upon the frame work of the machine, above the mixing drum 26, is a 85 cylindrical water tank or reservoir 44, provided on its interior, as shown in Fig. 8, with a horizontal partition or secondary bottom member 45, thus dividing the interior of the tank into two compartments. 90 An outlet pipe 46, leads from the compartment above the partition 45, into a quick operating valve 47, and also connected into said valve 47, is an inlet pipe 48, leading into the compartment below said partition 95 45. Disposed within the compartment of the tank 44, beneath the partition 45, is a pneumatic tire inner tube 49, and the valve thereof is secured through an aperture in the tank 44, as denoted by the reference 100 numeral 50, to permit attachment thereto of an air pump. A discharge pipe 51, leads from the compartment below the partition 45, in the tank 44, downwardly through a quick operating valve 52, into the hopper 31. 105

Journaled upon the shaft 24, is a cable drum 53, around which is wound a cable 54, which is led about an idler sheave 55, through another idler sheave 56, and then forwardly from the machine and through a 110 sheave 57, attached upon a stake 58, which is driven into the ground, and with the end of said cable returned and divided into a Y and fastened to eyes 59, upon the forward end of the machine, as shown in Fig. 2. A 115 ratchet wheel 60, is secured upon one end of the cable drum 53, and a brake drum 61, on the other end thereof, and feathered on the shaft 24, is a clutch element 62, adapted to be moved into locking engagement with a 120 complementary clutch member formed upon the hub of the brake drum to thereby lock said cable drum for rotation with the shaft 24. A horizontal bar 63, is secured between the uprights 5, at one side of the machine, 125 to carry the operating mechanisms for the various clutches upon the shaft 24, shown in Fig. 2. Mounted on one end of said bar 63, is a pawl 64, adapted to interlock with the ratchet wheel 60, and pivoted adjacent 130

thereto is a lever 65, which may be actuated to tilt said pawl 64, out of engagement with the ratchet wheel when so desired. Also pivoted upon said bar 63, adjacent the lever 65, is a lever 66, which is connected to a brakeband 67, disposed about the brake drum 61. Also pivotally mounted upon said bar 63, is a lever 68, for actuating the clutch member 62, and another lever 69, is likewise pivoted upon said bar 63, for actuation of the clutch member 29. As shown in Figs. 2 and 5, a shaft 70, is journaled through the sills 1, at the rear end of the machine, and secured upon the outer ends of said shaft 15 are nigger-heads 71, around which the drag cables 43, are wound, and each nigger-head 71, is provided with a ratchet wheel 72, with which a pivoted pawl 73, on each of the sill members 1, is adapted to engage.

Secured upon the forward end of the shaft 24, is a gear 74, which meshes with a pinion 75, which is secured upon a counter shaft having another gear 76, secured thereon, meshing in turn with a pinion 77, secured 25 upon the crank shaft of the motor 18. This mechanism affords a reduction drive to the shaft 24, and runs in oil incased in a housing 78. Pivotaly mounted upon the forward end of the machine in pivot brackets 79, which are secured upon the sills 1, is a platform housing 80, which normally is disposed downwardly in horizontal position, resting upon the sills 1, but may be swung upwardly into the dotted line position shown in Fig. 2, to give access to the motor 18. A stationary platform section 80^a, is provided on said frame over which the end of said pivoted section 80, laps when in closed position. The forward end of the 30 top surface of the hood or platform member 80, is recessed as indicated by the reference numeral 81, shown in Fig. 2, in dotted lines, to receive seated therein the ends of two run-ways 82, each held loosely attached 35 by a pin 83. Said run-ways are provided at their outer ends with rollers 84, as shown in Fig. 1, which track over the ground as the machine is moved along. Auxiliary run-ways 85, rest slidably upon each of said 40 run-way members 82, as shown in Fig. 1, with the outer ends thereof bearing in fixed relation upon the surface of the ground, so that as the machine moves along, said run-way members 82, slide therebeneath, thus 45 affording at all times means whereby a wheel-barrow may be wheeled up to and upon the platform 80, to discharge its contents into the hopper 31.

As shown in Fig. 11, the caster wheel 46 16, may be replaced by a stationary supporting foot 86, having an upright shaft, which extends through the bracket member 12, of the frame of the machine, and said upright shaft 87, is provided with a series 50 of transverse apertures 88, therethrough,

within which a pin may be inserted to sustain the weight of the frame thereon, so that the frame may be supported at different heights. A gasoline supply tank 89, to supply fuel to the motor 18, is mounted on the platform section 80^a, at one side of the hopper 31. A bottom pan 90, is secured beneath the motor 18, and transmission gearing between the side sills of the frame and the intermediate beam 4, and end sill 75 3, so that these mechanisms are entirely inclosed.

The operation is as follows:

In using this machine, it is first set up longitudinally on the foundation of the road or sidewalk over which the concrete is to be laid, and the stake 58, is driven into the ground and the cable 54, attached around the idler sheave 57, thereon, so that by actuation of the clutch lever 68, the cable 85 drum 53, may be caused to rotate, thereby drawing the machine as a whole forwardly toward the stake 58. As the machine is drawn away as the work progresses, the reinforcement fabric 40, is unwound from the reel thereof at the rear end of the machine, and the concrete flows through the spout 36, and down the chute 38, for distribution thereover. The concrete mixture used is generally of creamy consistency, so that it 95 is practically self leveling, and the tamping plate 42, which is drawn thereover at a considerable distance rearwardly of the machine serves to tamp and smooth the surface of the same. At the completion of a 100 day's mixing with the machine, and it being desirable to complete the tamping of the concrete which has been distributed, suitable cranks are engaged upon the squared ends of the shaft 70, to rotate the nigger-heads 71, and thereby draw the tamping pan or plate 42, inwardly and up to the end of the discharge chute 38. However, when the machine is moving and towing the tamping plate 42, the locking pawls 73, interlock 105 with the ratchet wheels 72, to prevent rotation of the nigger-heads 71. The crew which is working the machine and feeding the contents into the hopper 31, for introduction into the mixer 26, wheel their barrows up the inclined runways 58 and 82, and on to the platform 80, and at this point dump the contents of the barrow into the hopper 31, the gate valve 32, shown in Fig. 4, being closed. The proper amount of 110 water for the particular mixture is then admitted into the hopper 31, merely by closing the valve 47, serving to cut off communication between the compartment of the reservoir 44, above the partition 45, and the compartment below said partition, and the valve 52, permits the contents of the lower compartment to flow downwardly and into the hopper 31, after which upon 115 emptying of the mixer 26, through the spout 120

emptying of the mixer 26, through the spout 125

emptying of the mixer 26, through the spout 130

36, as the mixer rotates, the gate valve 32, is opened to admit the charge into the mixer from the hopper 31.

Inasmuch as the particular quantity of 5 water for different mixtures and purposes may vary, an ordinary pneumatic inner tube 49, is placed within the compartment below the partition 45, of the water tank, which, upon being inflated, displaces a certain space within said compartment so that 10 the quantity of water admitted thereinto may be varied. Of course, after the water has been admitted into the hopper 31, the valve 52, is closed and the valve 47, opened, 15 thereby allowing the main supply of water in the tank 44, to also enter into the compartment below the partition 45, again filling the same with a predetermined volume 20 of water for use in the next charge of material introduced into the machine.

Rotation of the mixer 26, is controlled by actuating the clutch lever 69, which serves to engage the clutch member 29, with the driving gear 28. It is evident by reference 25 to Fig. 2, that all of the operating mechanisms for the machine are at one side thereof, so that one person may easily control the entire operation thereof.

As will be seen by reference to the plan 30 view shown in Fig. 5, the front rollers 16, are spaced apart from their inner ends an amount substantially equal to the length of the associated rollers 10 and 11, and the forward end of the machine being of considerable weight, as the same is drawn away 35 from the work, said front rollers 16, track deeper into the ground, as shown in Fig. 2, than the rear rollers 10 and 11, following the same, thus affording a groove or trough 40 at each side of the surface over which the concrete is spread. By changing the rollers 10 and 11 and the front casters 16, the width of the road or walk may be changed, either increased or diminished.

45 This machine is also well adapted for stationary work, the stationary supporting feet 86, being used for the purpose to prevent movement of the machine and the cable drum may be then used for hoisting purposes. The auxiliary corner blocks 91, are secured on the rear end of the frame to receive a set of the stationary feet attached 50 therein whereby the entire machine may, if necessary, be supported at its four corners 55 independent of rollers.

I am aware that various details of construction of this invention may be varied through a wide range without departing from the principles of this invention, and I 60 therefore do not purpose limiting the patent granted, otherwise than necessitated by the prior art.

I claim as my invention;

1. In a machine of the class described, a 65 concrete mixer, a frame on which the same

is mounted, a power plant, means transmitting a drive from the power plant to said mixer and permitting said drive to be disconnected, a windlass on the frame, a cable attached thereon, adapted to be attached to a fixed point to move said frame when the windlass is driven by the power plant, means admitting a predetermined quantity of water into the mixer with each charge of material admitted thereto, and a housing 75 for the power plant pivoted on said frame and affording a loading platform for discharge of material into the mixer.

2. In a machine of the class described, a frame, rollers on which the same is supported, a power plant mounted on said frame, a pivotally mounted housing thereover affording a loading platform, a rotatable mixer on said frame, releasable driving connections between said mixer and said power plant, a feed hopper at one end of said mixer adjacent said loading platform, a frame work extending upwardly around the mixer, a water reservoir thereabove, and valved connections for discharging the 90 water from said water reservoir into the hopper for introduction into the mixer.

3. In a machine of the class described, a frame, rollers supporting the same, a power plant on said frame, a cylindrical mixer rotatably mounted thereon, a jack shaft driven by the power plant, a gear thereon, a ring gear on said mixer meshing therewith, a clutch for locking said first mentioned gear on said jack shaft to cause rotation of the 100 mixer thereby, a windlass journaled on said jack shaft, a clutch locking the same to said jack shaft whereby the windlass is driven thereby, a cable wound about said windlass adapted to be attached to a fixed point 105 whereby the machine may be drawn forwardly over the ground away from the work as the work progresses, a reel of reinforcement material adjustably mounted at the rear end of the machine, automatically 110 unreeled over the surface to be covered with concrete as the machine is drawn away from the work, and means admitting predetermined quantities of water into the mixture admitted into the mixer.

4. In a machine of the class described, a power plant, a mixer thereon, driving connections between the mixer and the power plant, a water reservoir, disposed above the mixer, a compartment therein of variable 120 volume to receive predetermined quantities of water therein for discharge into the mixer, a charging hopper for said mixer, a pivotally mounted cover for said power plant affording a loading platform for introduction of material into the hopper, and means carrying a gravity acting reel of reinforcement material at one end of the machine to be unreeled for disposition over the surface on which the concrete is dis- 125

charged from the mixer as the machine is moved along.

5. The combination with a concrete mixing machine, of chambered means mounted thereon adapted to introduce predetermined quantities of water into the machine, and pneumatic means within said chambered means for varying the volume of water adapted to be admitted into said

10 chambered means.

6. The combination with a concrete mixing machine, having a rotatable mixing drum, of a tank mounted on the machine, having an upper and lower compartment,

and means connecting said compartments; 15 for filling the lower compartment from the upper compartment, pneumatic means for varying the volume of said lower compartment, and means for discharging from the lower compartment into the revolving drum. 20

In testimony whereof I have hereunto subscribed my name in the presence of two subscribing witnesses.

WILLIAM DEANE HAM.
